UNITED STATES PATENT OFFICE.

HOWARD A. DUDLEY, OF HAGERSTOWN, MARYLAND.

LOOSE-LEAF BINDER.

Application filed November 17, 1921. Serial No. 515,846.

To all whom it may concern:

Be it known that I, HOWARD A. DUDLEY, a citizen of the United States, residing at Hagerstown, in the county of Washington and State of Maryland, have invented new and useful Improvements in Loose-Leaf Binders, of which the following is a specification.

This invention relates to loose-leaf binders and particularly to that class of binder in which a cover member is provided on its inside with spaced hinged flaps arranged in parallel relation to one another and having leaf-holding means passing through registering apertures in said flaps.

One of the objects of the invention is the provision of leaf-holding means comprising a pair of adjacent slidably arranged elements removably inserted from opposite directions through apertures in the flaps, said elements constituting a leaf-holding bar longitudinally extensible to accommodate the divergence of the hinged flaps when the body of leaves is opened.

Another object of the invention is the provision of a two-part leaf-securing bar insertable through a cylindrical perforation in the body of leaves and lying axially thereof when the body of leaves is closed, the parts of said bar being so constructed as to assume relative angularity to one another corresponding to the angular deviation from its axis of the two sections into which the cylindrical perforation is divided when the body of leaves is opened.

Another object of the invention is the provision of a leaf-holding bar comprising pins having flat contacting surfaces, and having the inner end portions thereof tapered in planes parallel to the plane of their flat surfaces, said pins being insertable from opposite directions through non-circular apertures in the hinged flaps and through the cylindrical perforation in the body of leaves, said pins being held by the non-circular apertures in a position in which the tapered portions of the upper sides thereof will permit the pins to assume an angular relationship corresponding to the angular deviation of the two sections of said cylindrical perforation when the body of leaves is opened.

With the above and other objects in view, my invention consists in the improved loose-leaf binder illustrated in the accompanying drawings, described in the following specification, and particularly claimed, and in

such variations and modifications thereof as will be obvious to those skilled in the art to which my invention relates.

In the drawings accompanying and forming a part of this specification, and wherein the preferred embodiment of my invention is illustrated:—

Figure 1 is an elevational cross section of one end of the loose-leaf binder taken in the plane of the leaf-securing bar.

Figure 2 is a similar view showing the body of the leaves in open position.

Figure 3 is a plan view of the loose-leaf binder open at the first leaf.

Figure 4 is a view in cross section taken along the line 4—4 of Figure 3.

Figure 5 is a detail view showing the elements of the leaf-holding bar.

Figure 6 is a plan view of a modified form of a loose-leaf binder open at the first leaf, portions thereof being broken away.

Figures 7 and 8 are views respectively in elevation and plan of the leaf-holding bar.

Referring in detail to the several figures of the drawing the numerals 1 and 2 represent the front and rear covers of the loose-leaf binder which are preferably made of an integral piece of material and may be stiff or flexible, as preferred. This piece of material includes an intermediate portion 3, forming the back of the binder, and is made permanently convex by having secured thereto the solid convex back-piece 4 which has a flat upper side 5 lying substantially flush with the front and rear covers of the binder when the latter is opened flat. Said covers are foldable along the edges of the back-piece 4 and are provided along the folds with hinged flaps 6 and 7 each of which is made of fabric or other flexible material folded to form a flange 8 which is pasted or otherwise fixed to the inner side of the coverpiece. The material forming the hinged flap is folded upon itself as at 9, a metallic reinforcing strip 10 being retained within the fold and secured in place by means of eyelets 11 and 12, best shown in Figure 3, by which the folded portions of the hinged flap are held together. At suitable spaced points somewhat adjacent the upper and lower ends of the binder the hinged flaps 6 and 7 and the metallic strips 10 contained therein are provided with oppositely arranged non-circular apertures 11, each having a flat side, the flat side of the

105

110

116

aperture in the one strip being in alignment with the flat side of the aperture of the other strip, the apertures in the two flaps being arranged on opposite sides of the common plane embracing their flat sides.

Each of these apertures is provided with a pin 14 and 15 insertable therethrough from opposite sides, the length of which is substantially equal to the distance apart of

- 10 the hinged flaps when in parallel relation to one another. The pins are headed at one end as shown at 16 and the heads are seated in countersunk depressions in the hinged flaps. One side of each pin is flattened so
- 15 that said pin fits the aperture in which it is inserted in a non-rotatable manner. The portions of the sides of said pins remote from the head are tapered in planes corresponding to the plane of their flattened surfaces as shown at 18.
- 20

When said pins are inserted in the appropriate apertures in the hinged flaps, their flat surfaces are substantially in contact and capable of sliding relative to one another, 25 to allow for divergence of the hinged flaps when the body of leaves 19, held therein, is opened, permitting a substantially flat opening of the leaves. Said body of leaves is provided with a cylindrical perforation into 30 which the pins 14 and 15 comprising the leaf-holding bar are inserted. When the body of leaves is divided into two portions in the act of opening the same, the cylindrical perforation will be separated into two 35 sections which deviate angularly downward from the center of the cylindrical perforation. While portions of the pins adjacent the heads thereof may fit the adjacent sections of said cylindrical perforation more or less 40 snugly, the tapered shape of their inner portions permits a play between each pin and that section of the cylindrical perforation adjacent its inner portion, so that when the body of leaves is opened the pins are free 45 to assume relatively angular positions to correspond to the angular deviation of the two parts of the cylindrical perforation through which they extend.

It is obvious that the angular deviation 50 of the cylindrical perforation in the body of leaves will always be downward from the center and that the pins, therefore, need be tapered only on one side, in order to perfectly perform their function. By tapering 55 them on both sides, however, as shown in Figure 7, the pins are rendered interchangeable so that no confusion need arise when assembling the binder, in mating up the correct pins to form a pair.

60 When the binder is opened, frictional resistance of the tapered inner end portion of each pin with that part of the cylindrical perforation with which it coacts prevents the inadvertent withdrawal of the pin from 65 the cylindrical perforation, and when the

binder is closed the front and rear cover portions preclude the accidental displacement of the pins. No locking means is therefore necessary and by opening either cover the pins on that side may be readily 70 withdrawn to permit taking out of the leaves or the insertion of new leaves.

One of the drawbacks heretofore experienced in loose-leaf binders is the difficulty of keeping the leaves in alignment when it 75 is desired to withdraw an intact portion of the body of leaves in order to remove a particular intermediate leaf from said binder. In this device it is only necessary to open the binder at the first leaf, remove the pins 80 from the front flap so as to release the latter, replace the pins in the body of leaves, grasp the bundle of leaves which is to be withdrawn without removing the pins, and to lift it bodily from the binder with one pin 85 of each pair in place. The desired leaf may then be removed and the bundle returned to its original position without disturbing the alignment of the cylindrical perforations therethrough.

90 Figure 6 shows a slight modification of the structure shown in Figure 3, the difference being that four pairs of leaf holding bars are used instead of two pairs as shown in the device already described. This is for the purpose of preventing any slight displacement or misalignment in the leaves secured within the binder such as might happen at the point where one of the pins terminates short of the other as shown at 21 in Figure 100 2. In this case the perforations in the leaves which are retained by the single pin are larger in one direction than the pin by which they are retained permitting a shifting of the leaves in this direction.

105 By providing the hinged flaps with double the number of flat sided apertures and arranging the flat sides of the inner pair in a direction opposite to the flat sides of the outer pair, shifting of the leaves will 110 be prevented even though the leaves be retained by only one pin of each pair.

115 Although I have thus described the preferred embodiment of my invention, it is evident that those skilled in the arts to which this relates may make various changes in the construction, combination and arrangement of the several parts without departing from the spirit and scope of the invention.

120 Having described my invention what I claim as new and desire to secure by Letters Patent, is:—

1. In a loose-leaf binder, a cover comprising front and rear portions foldable on each side of an intermediate portion, hinged flaps secured to the inside of the cover along the folds, said flaps being provided with oppositely arranged non-circular apertures and cooperating pins having heads engaged by 125

said flaps, fitting said apertures and inserted in opposite directions one through each aperture, said pins being relatively slidable and together forming a leaf-holding bar.

5 2. In a loose-leaf binder, a cover comprising front and rear portions foldable on each side of an intermediate portion, hinged flaps secured to the inside of the cover along the folds, said flaps being provided with oppositely arranged apertures each of which is formed with a flat side, the flat sides of both apertures lying in a plane at right angles to the direction of fold of the cover portions, and the apertures themselves lying on opposite sides of this plane, cooperating pins having heads engageable by said flaps, fitting said apertures and inserted in opposite directions one through each aperture, said pins being relatively slidable and together forming a leaf-holding bar.

15 3. In a loose-leaf binder, a cover comprising front and rear portions foldable on each side of an intermediate portion, hinged flaps secured to the inside of the cover along the folds, said flaps being provided with oppositely arranged non-circular apertures, cooperating pins fitting said apertures and insertable in opposite directions one through each aperture, said pins having co-acting flattened faces lying in a plane at right angles to the direction of fold of the cover portions, said pins being relatively slidable and together forming a leaf-holding bar.

25 4. In a loose-leaf binder, a cover comprising front and rear portions, foldable on each side of an intermediate portion, hinged flaps secured to the inside of the cover along the folds, said flaps being provided with oppositely arranged non-circular apertures, operating pins fitting said apertures and insertable in opposite directions one through each aperture, said pins having co-acting flattened faces lying in a plane at right angles to the direction of fold of the cover portions, the lower portion of the upper side of each pin being tapered, said pins being relatively slidable and together forming a leaf-holding bar.

35 5. In a loose-leaf binder, a pair of headed pins oppositely arranged, each having a flat face slidably engaging the flat face of the other, the inner end portion of each of said pins being tapered at one side in a plane parallel to the plane embracing their flat faces.

45 6. In a loose-leaf binder, a cover comprising front and rear portions foldable on each side of an intermediate portion, hinged flaps secured to the inside of said cover along the folds, each flap comprising a folded piece of

flexible material having a metallic reinforcing piece inserted therebetween, said flaps being provided with oppositely arranged non-circular apertures surrounded by counter-sunk depressions on the outer side, cooperating pins fitting said apertures having heads seated in said countersunk depressions and inserted in opposite directions one through each aperture, said pins having coacting flattened faces lying in a plane in right angles to the direction of fold of the cover portions, said pins being relatively slidable and together forming a leaf-holding bar.

55 7. In combination with a body of leaves having a cylindrical perforation therethrough which is divided into two parts with axis deviating from a straight line when the body of leaves is open, a loose-leaf binder comprising front and rear cover portions foldable on each side of an intermediate portion, hinged flaps secured to the inside of the cover portions along the folds, said flaps being provided with oppositely arranged non-circular apertures, cooperating pins fitting said apertures and inserted in opposite directions one through each aperture and through said cylindrical perforation, said pins having slidably engaging flattened faces lying in the plane of angular deviation of the parts of said cylindrical perforation, said pins each having the upper side thereof tapered at its inner end to permit relative angular displacement of said pin corresponding to the angular deviation of said parts of said cylindrical perforation.

8. In a loose-leaf binder, a cover comprising front and rear portions foldable on each side of an intermediate portion, hinged flaps secured to the inside of the cover along the folds, said flaps being provided with a plurality of cooperating pairs of apertures each of which is formed with a flat side, the flat sides of some of the apertures in each flap being arranged in an opposite direction to the flat sides of the remaining apertures, cooperating pins fitting said apertures and inserted in opposite directions one through each aperture, said pins each having coacting flattened faces lying in a plane at right angles to the direction of fold of the cover portions said pins being relatively slidable and together forming a leaf-holding bar.

In testimony whereof I have hereunto set my hand in presence of two subscribing witnesses.
